ELECTRON DISCHARGE DEVICE

George Ross Kilgore, Verona, N. J., assignor to
 Radio Corporation of America, a corporation of
 Delaware

Application April 24, 1942, Serial No. 440,298

19 Claims. (Cl. 315—12)

1

My invention relates to electron discharge devices utilizing periodic electron beam deflection and particularly useful at ultra high frequencies.

In conventional electron discharge devices of the type under consideration, a beam of electrons is directed between a pair of deflecting electrodes toward an apertured electrode, behind which is usually placed a collector. Alternating high frequency voltages are applied to the deflecting electrodes to cause the electron beam to be deflected across the aperture to thus control the instantaneous flow of electron current to the collector, which may be used as an output electrode. In such conventional types of tubes the deflecting sensitivity drops off as the frequency at which the tube is operated is increased due to electron transit time effects. Efforts have been made to increase the deflection sensitivity or the transconductance of the tube but such efforts have not met with a great deal of success. Conventional tubes of this kind are also subject to the limitation that when operated at ultra high frequencies the input circuit tends to be of low resonant impedance resulting in an excessive amount of power being required to drive the tube. This decreases the effective power gain of the tube when operated as an amplifier. Fundamental causes of low resonant impedance include, among other things, radiation and resistance losses due to high circulating current in electrodes and leads. Electron loading also results from the interaction of the electron stream and the circuits connected to the tube and electrodes and may cause undesired degenerative and regenerative effects caused by lead impedances common to more than one circuit.

It is an object of my invention to provide an electron discharge device of the beam deflection type, which is particularly suitable for use at ultra high frequencies and which has a comparatively high transconductance.

It is another object of my invention to provide such a device utilizing an input circuit having high resonant impedance, thus making more effective the use of the driving power.

A further object of my invention is to provide such a device in which undesired coupling due to common leads and ineffective shielding between circuits is reduced to a minimum.

Another specific object of my invention is to provide an electron discharge device of the beam deflection type, utilizing multiple additive deflection for providing a tube having high transconductance.

A still further object of my invention is to

2

provide an electron discharge device of the beam deflection type utilizing additive multiple deflection and secondary emission amplification for producing a tube having very high transconductance.

5 A still further object of my invention is to provide an electron discharge device of the beam deflection type utilizing a novel type of combined electrode system and circuit useful at ultra high frequencies and having a high transconductance.

10 The novel features which I believe to be characteristic of my invention are set forth with particularity in the appended claims, but the invention itself will best be understood by reference 15 to the following description taken in connection with the accompanying drawings in which Figure 1 is a longitudinal section of one form of an electron discharge device made according to my invention and its associated circuit, Figure 2 is 20 a transverse section taken along the line 2—2 of Figure 1, Figure 3 is a longitudinal section of a modification of an electron discharge device made according to my invention, Figure 4 is a transverse section taken along the line 4—4 of 25 Figure 3, Figure 5 is an enlarged sectional view taken along the line 5—5 of Figure 3, Figure 6 is a perspective of the electrode system and high frequency circuit made according to my invention and utilized in the tube shown in Figure 3, and 30 Figure 7 is a schematic longitudinal section of the tube shown in Figure 3 made according to my invention and a diagram of its associated circuit.

35 Referring to Figure 1, an electron discharge device made according to my invention includes an evacuated envelope 10 having the usual press 11 and base 12. Supported from this press is the indirectly heated cathode 13 provided with leads 13' which act as the cathode lead and heater leads. Mounted at the other end of the envelope is a collector 14 toward which the beam is directed through the intermediate electrodes positioned between the cathode and collector.

40 Adjacent the cathode is the apertured beam forming and focusing electrode in the form of a disc 15 electrically connected to the lead 15'. The deflecting electrode system includes the tubular member 16 separated into compartments or chambers by means of the transverse conducting elements 17, 18 and 19 provided with the aligned apertures 17', 18' and 19' through which the beam from the cathode is directed during operation of the electron discharge device. The beam in passing through this deflecting electrode 45 system passes through another apertured elec-

trode 20 having the aperture 20' and connected to the lead and support 21. Positioned between this apertured electrode and the collector is the electron multiplying system comprising electrodes 22, 23, 24, 25, 26 and screen 27. The element 20" maintained at ground potential by being connected to electrode 20 causes the beam to be directed against the surface of the element 22 to cause the emission of secondary electrons when struck by the beam of primary electrons. These electron multiplying electrodes may be coated with the usual material for inducing a high ratio of primary-to-secondary electrons.

In accordance with my invention, I position between the apertured conducting members 18 and 19 the successively positioned oppositely disposed deflecting electrode elements 30, 31 and 32. The distance between the centers of these deflecting elements is equal to the distance traveled by an electron during a half period of the controlling voltage applied to these deflecting electrodes. These elements preferably have a dimension in the direction of travel of the electron beam equal approximately to the distance travelled by an electron during a half period or π radians. The successive elements are cross connected so that the phase relationship between the electron beam and the voltage applied to the controlling electrode elements will cause additive deflection, that is deflection in the same direction.

The lines 34 and 35 are connected to the signal input circuit as shown and to the voltage divider arrangement 33 through the resistance 37 and 38 which cooperate with the shorting condenser 36. This arrangement permits not only tuning of the lines 34 and 35 but provides the necessary direct voltages for applying the proper biasing or polarizing voltages to the deflecting electrodes to center the electron beam. The proper positive voltage is applied to deflecting electrode system 16 by means of the conductor 39, and the voltage source for the multiplier elements is shown at 40, the voltages increasing in a positive direction from the apertured member 20 to the collector 14. By-passing condensers, such as 41, provide paths for the radio frequency currents. The output is taken between collector 14 and screen 27 across the circuit comprising the primary of transformer 42 and condenser 43, the proper biasing voltage on the collector being provided by means of conductor 43', by-passing condenser 44 completing the radio frequency circuit and permitting different positive voltages to be applied to the member 16 and the collector 14.

In operation a beam of electrons is directed from the cathode 13 through the beam forming and electron lens system formed by elements 15 and elements 17 and 18. By properly positioning deflecting elements 30 with respect to apertured element 18 another electron lens can be provided between these elements to properly focus the beam on the aperture 19' of apertured element 19. The beam may also be properly directed by applying the bias to the three deflecting elements, an odd number of elements being provided for this purpose. The beam is deflected across aperture 19' when an input signal voltage or control voltage is applied through the conductors 34 and 35. The transit time of the electrons is so matched to the deflecting elements that any electrons which may have been deflected in an upward direction by deflecting electrodes 30 will arrive between elements 31 a half period later and again be deflected in the same direction, likewise arriving between elements 32 to be again

deflected in the same direction. Since the elements are cross-connected and since centers are positioned a half period apart, the voltages between deflecting electrodes will always be in the proper phase to cause additive deflection of any group of electrons in the same direction.

The amount of deflection across apertured element 19 at any particular instant determines the amount of current flowing through the aperture so that the input voltage may be reproduced and the output much amplified because of the high transconductance of the tube. This amplification is still further increased by means of the multiplier system positioned between the apertured member 20 and collector 14, the output being taken between the collector 14 and screen 27 by means of the output circuit comprising transformer 42 and condenser 43. If it is desired to utilize the device as a converter it would be possible to do this by introducing both signal and local oscillator voltages on the input or Lecher wires 34 and 35.

In Figure 3 is shown a modification of my invention in which the input circuit is self-contained and in which the input circuit is substantially completely shielded from the cathode electrode as well as the output electrode system. This input circuit incorporates a modified form of the multiple deflection arrangement shown in Figure 1.

In this embodiment the evacuated envelope 50 is provided with the usual press 51 and base 51'. Supported on the press is an indirectly heated cathode 52 provided with a cathode lead 53. Next adjacent the cathode is the beam forming and focusing electrode 54 supported by means of a glass bead support construction 54'. The electrode 54 and cathode 52 are electrically connected as shown in Figure 5. Mounted at the other end of the envelope is the collector 55 provided with supporting leads 55'. Positioned between the focusing electrode 54 and collector 55 is the beam deflecting electrode system comprising the tubular member 56 having extending thereacross the apertured disc-like conducting elements or partitions 57, 58 and 59 provided with the elongated slots 57', 58' and 59' which are aligned with each other and with the aperture 54' in the focusing element 54. The length of these elongated slots varies as shown for the purpose of properly forming the beam.

In accordance with my invention the deflecting electrode system and input circuit are combined into a unitary structure which simplifies the construction and permits effective shielding of the input circuit and electrodes from the output electrode system. The tubular member 56 is provided with the extensions 60 and 61 and it is within these extensions that the combined deflecting electrode system and circuit are mounted and supported by means of glass bead supporting structures 63 and 63'.

As best shown in Figure 6, the deflecting electrode system comprises an elongated rectangularly shaped member of ribbon-like construction having intermediate its ends inwardly extending sections 64 provided with slots 65 for forming deflecting elements 64' between said slots. The distance from the center line extending transversely of the slotted portion to an end of the rectangularly shaped member is equal to a quarter-wave of the received or controlling voltage, so that in effect each half acts like a Lecher wire system of quarter wave-length, the voltage peak appearing between the inwardly extending por-

tions 64 in which the deflecting electrode elements are positioned. The voltage is fed to this circuit arrangement by means of leads 66 which may be connected to a transmission line system, for example, of the coaxial cable type. The distance between centers of the elements 64' is equal to the distance that an electron travels during one period of the applied controlling voltage or electrically to 2π radians, the elements having a width in the direction of travel of the electron beam substantially equal to a half-period or π radians. This arrangement makes it possible to connect all elements on the same side of the beam, electrically together, and to the same side of the Lecher wire system formed by the structure 62.

To properly center the beam between the deflecting electrode elements and to direct it through the apertured member 59, I provide a pair of beam directing elements 67 in the chamber between partitions 57 and 58, the proper biasing voltages being applied by means of the leads 68.

The schematic wiring diagram shown in Figure 7 illustrates the connections to the voltage divider system 71 and the voltage or potential source 78 for the beam directing electrodes 67 and the various other electrodes. The output is taken between the collector 55 and the transverse conducting member 59 supported by tubular element 56 across the inductance element 72. It will be observed that a wire or conductor 591 is positioned centrally of the aperture to provide the double apertured effect for obtaining the desired output characteristics.

In operation the electron beam formed by cathode 52 and focusing element 54 is directed through aperture 57 between the beam directing elements 67, upon which the bias may be properly adjusted to center the beam on aperture 58' and to direct it through the deflecting electrode system between the pairs of successively positioned oppositely disposed beam deflecting elements 64'. As the electron beam passes between the elements it comes under the influence of each successive pair of elements for approximately a half-period at half-period intervals. Inasmuch as the voltage during the half-period intervals passes through 180° , deflection of the beam will be additive or in the same direction, thus effective transconductance is increased substantially in direct ratio to the number of successive pairs of deflecting elements. In the arrangement shown the input circuit is combined with the deflecting elements to greatly simplify this structure, to make more effective the deflection control, and because of the shielding arrangement of the tubular member 56 and extensions 69 and 61 the input circuit is well shielded from the output electrode system, so that little if any interaction results.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having cathode means for providing a directed beam of electrons

and an output electrode system for receiving said electrons, and means positioned between the cathode means and the output electrode system through which said electron beam is directed, and including a plurality of successive pairs of oppositely disposed deflecting elements between which the beam is directed, said elements being adapted to have an alternating control voltage of high frequency applied thereto, the spacing between the centers of the elements of different pairs being equal to the distance travelled by an electron during a cycle of the applied controlling voltage.

2. An electron discharge device having cathode means for providing a directed beam of electrons and an output electrode system for receiving said electrons, and means positioned between the cathode means and the output electrode system through which said electron beam is directed, and including a plurality of successive pairs of oppositely disposed deflecting elements between which the beam is directed, said elements being adapted to have an alternating control voltage of high frequency applied thereto, the spacing between the centers of the elements of different pairs being equal to the distance travelled by an electron during a cycle of the applied controlling voltage, all of the elements on the same side of the beam path being electrically connected together.

3. An electron discharge device having cathode means for providing a directed beam of electrons and an output electrode system for receiving said electrons, and means positioned between the cathode means and the output electrode system through which said electron beam is directed, and including a plurality of successive pairs of oppositely disposed deflecting elements between which the beam is directed, said elements being adapted to have an alternating control voltage of high frequency applied thereto, the spacing between the centers of the elements of different pairs being equal to the distance travelled by an electron during a cycle of the applied controlling voltage, all of the elements on the same side of the beam path being electrically connected together, and a conducting loop connected between the elements on opposite sides of the beam path.

4. An electron discharge device having cathode means for providing a directed beam of electrons, means for receiving said electrons, apertured means positioned between the cathode means and the receiving means through which said electron beam is directed to said receiving means, and including a plurality of successive pairs of oppositely disposed deflecting elements adapted to have an alternating control voltage of high frequency applied thereto, the spacing between the centers of the elements being equal to the distance travelled by an electron in a cycle of the applied controlling voltage, each pair of deflecting elements being spaced from the next succeeding pair of elements a distance equal to the dimension of said elements in the direction of travel of the electron beam.

5. An electron discharge device having a cathode for supplying a beam of electrons and an output electrode system toward which said electrons are directed, and means positioned between the cathode and the output electrode system for subjecting said beam to additive successive deflection and including a conducting enclosure through which the beam of electrons is directed, said conducting enclosure having transverse elements provided with aligned apertures, and a

plurality of successive pairs of oppositely disposed deflecting elements positioned between the transverse elements and between which said beam of electrons is directed during operation of said electron discharge device, the spacing between the centers of said elements being equal to the distance travelled by an electron in a cycle of the applied alternating control voltage said output electrode system including an apertured electrode through which the beam of electrons is directed, and a plurality of secondary emitting electrode elements upon which said beam is directed.

6. An electron discharge device having a cathode means for supplying a directed beam of electrons, and an output electrode system toward which said electrons are directed, a tubular conducting member positioned between the cathode and output electrode system through which said beam is directed, and having a plurality of transverse conducting elements having apertures aligned and through which the beam of electrons is directed, and a plurality of successively positioned pairs of deflecting electrode elements positioned between the transverse apertured elements, said pairs of deflecting electrode elements being cross connected with the next succeeding pair of deflecting electrode elements.

7. An electron discharge device having a cathode means for supplying a directed beam of electrons, and an output electrode system toward which said electrons are directed, a tubular conducting member positioned between the cathode and output electrode system through which said beam is directed, and having a plurality of transverse conducting elements having apertures aligned and through which the beam of electrons is directed, and a plurality of successively positioned pairs of deflecting electrode elements positioned between the transverse apertured elements, said pairs of deflecting electrode elements being cross connected with the next succeeding pair of deflecting electrode elements, said output electrode system including an apertured electrode and a collector.

8. An electron discharge device having a cathode means for supplying a directed beam of electrons, and an output electrode system toward which said electrons are directed, a tubular conducting member positioned between the cathode and output electrode system through which said beam is directed, and having a plurality of transverse conducting elements having apertures aligned and through which the beam of electrons is directed, and a plurality of successively positioned pairs of deflecting electrode elements positioned between the transverse apertured elements, said pairs of deflecting electrode elements being cross connected with the next succeeding pair of deflecting electrode elements, said output electrode system including a secondary electron emitting means.

9. An electron discharge device having a cathode means for supplying a directed beam of electrons, and a collector toward which said electrons are directed, and a deflecting electrode means positioned between the cathode means and the collector and including a conducting enclosing member having a plurality of transverse elements provided with aligned apertures through which said beam of electrons is directed, and a deflecting electrode system within said conducting enclosing member and comprising an elongated rectangular shaped conducting loop having intermediate its ends a plurality of opposite-

ly disposed slots forming a plurality of oppositely disposed deflecting elements through which the beam of electrons is directed.

10. An electron discharge device having a cathode means for supplying a directed beam of electrons, and a collector toward which said electrons are directed, and a deflecting electrode means positioned between the cathode means and the collector and including a conducting enclosing member having a plurality of transverse elements provided with aligned apertures through which said beam of electrons is directed, and a deflecting electrode system comprising an elongated rectangular shaped conducting loop having intermediate its ends a plurality of oppositely disposed slots for forming a plurality of oppositely disposed deflecting elements through which the beam of electrons is directed, said conducting loop lying within said conducting enclosing member and extending through the sides of the conducting enclosing member and extensions on said conducting enclosing member for shielding the ends of said conducting loop.

11. An electron discharge device having a cathode means for supplying a directed beam of electrons, and a collector toward which said electrons are directed, and a deflecting electrode means positioned between the cathode means and the collector and including a conducting enclosing member having a plurality of transverse elements provided with aligned apertures through which said beam of electrons is directed, and a deflecting electrode system comprising an elongated rectangular shaped conducting loop having intermediate its ends a plurality of oppositely disposed slots for forming a plurality of oppositely disposed deflecting elements through which the beam of electrons is directed, said conducting loop lying within and extending through the sides of the conducting enclosing member and extensions on said conducting enclosing member for shielding the ends of said conducting loop, and a pair of beam directing electrodes positioned between the cathode means and the deflecting electrode system.

12. An electron discharge device having cathode means for supplying a directed beam of electrons and electrode means for receiving said beam of electrons, an apertured element positioned adjacent the receiving electrode means and having an aperture registering with said receiving electrode means, a deflecting electrode system positioned between the cathode means and the apertured means and including an elongated rectangularly shaped conducting member through which the beam of electrons is directed, and having slots on opposite sides of said member intermediate the ends of said member for providing a plurality of successively positioned oppositely disposed pairs of deflecting elements between which said beam passes.

13. An electron discharge device having cathode means for supplying a directed beam of electrons and electrode means for receiving said beam of electrons, an apertured element positioned adjacent the receiving electrode means and having an aperture registering with said receiving electrode means, a deflecting electrode system positioned between the cathode means and the apertured means and including an elongated rectangularly shaped conducting member through which the beam of electrons is directed, said member having slots on opposite sides intermediate the ends of said member for providing a plurality of successively positioned oppositely dis-

posed pairs of deflecting elements between which said beam passes, the distance between centers of successive pairs of deflecting elements being equal to the distance travelled by an electron during a cycle of the applied controlling voltage.

14. An electron discharge device having cathode means for supplying a directed beam of electrons and electrode means for receiving said beam of electrons, an apertured element positioned adjacent the receiving electrode means and having an aperture registering with said receiving electrode means, a deflecting electrode system positioned between the cathode means and the apertured means and including an elongated rectangularly shaped conducting member through which the beam of electrons is directed, said member having slots on opposite sides intermediate the ends of said member for providing a plurality of successively positioned oppositely disposed pairs of deflecting elements between which said beam passes, and means including rod-like elements positioned between the cathode means and deflecting electrode system for controlling the direction of the electron beam between the cathode and the deflecting electrode system.

15. An electron discharge device having cathode means for supplying a directed beam of electrons and electrode means for receiving said beam of electrons, an apertured element positioned adjacent the receiving electrode means and having an aperture registering with said receiving electrode means, a deflecting electrode system positioned between the cathode means and the apertured means and including an elongated rectangularly shaped conducting ribbon-like loop through which the beam of electrons is directed, said loop having slots on opposite sides intermediate the ends of said loop for providing a plurality of successively positioned oppositely disposed pairs of deflecting elements between which said beam passes, the loop having thickened portions in which said slots are formed.

16. An electron discharge device having a cathode for supplying electrons, and means for forming said electrons into a directed beam, and means for receiving said beam, means intermediate said beam forming means and said beam receiving means and including a tubular member having its longitudinal axis coinciding with the path of the electron beam and provided with a plurality of transverse conducting members having aligned apertures through which the beam is directed, a pair of beam directing electrodes positioned between two of said transverse conducting members and a beam deflecting electrode system positioned between another pair of transverse conducting members, and including an elongated rectangularly shaped conducting loop extending through opposite sides of the tubular member and hav-

ing a plurality of successively positioned deflecting electrode elements intermediate the ends of said loop and positioned on opposite sides of the path of said electron beam, and shielding extensions supported on said tubular member and surrounding the ends of said conducting loop.

17. An electron discharge device having a cathode for supplying electrons, and means for forming said electrons into a directed beam, and means for receiving said beam, means intermediate said beam forming means and said beam receiving means and including a tubular member having its longitudinal axis coinciding with the path of the electron beam between the cathode and the receiving means and provided with a plurality of transverse conducting members having aligned apertures through which the beam is directed, and a beam deflecting electrode system positioned between a pair of said transverse members, and including an elongated rectangularly shaped conducting loop extending through opposite sides of the tubular member and having a plurality of successively positioned deflecting electrode elements intermediate the ends of said loop and positioned on opposite sides of the path of said electron beam, and shielding extensions supported on said tubular member and surrounding the ends of said conducting loop.

18. An electron discharge device having a cathode for supplying a beam of electrons, and means for receiving said beam of electrons, an apertured transverse conducting member between said cathode and means for receiving said beam of electrons, a beam deflecting electrode system positioned between the apertured conducting member and said cathode, and including an elongated rectangularly shaped conducting loop having a plurality of successively positioned oppositely disposed slots on opposite sides thereof forming a plurality of deflecting electrode elements intermediate the ends of said loop and between which elements the electron beam is directed during operation of said electron discharge device.

19. An electron discharge device having cathode means for providing a directed beam of electrons, and an output electrode system for receiving said electrons, means positioned between the cathode means and the output electrode system through which the electron beam is directed and including a plurality of successive pairs of oppositely disposed deflecting electrodes through which said beam is directed, said elements being adapted to have an alternating control voltage of high frequency applied thereto, the spacing between the elements of different pairs being equal to the distance travelled by an electron during a multiple of cycles of the applied controlling voltage.

GEORGE ROSS KILGORE.
